UNITED STATES PATENT OFFICE.

HENRY S. GILBERT, OF CHAMBERSBURG, PENNSYLVANIA.

DESIGN FOR A COMBINATION TOOL.

Application filed March 19, 1926. Serial No. 16,986. Term of patent 7 years.

To all whom it may concern:

Be it known that I, HENRY S. GILBERT, a citizen of the United States, residing at Chambersburg, in the county of Franklin and State of Pennsylvania, have invented a certain new, original, and ornamental Design for Combination Tools, of which the following is a specification, reference being had to the accompanying drawings, forming part thereof.

Fig. 1 is a front elevational view of a combination tool showing my new design, and Fig. 2 is a side elevational view thereof.

I claim:

The ornamental design for a combination tool, as shown.

HENRY S. GILBERT.
